UNITED STATES PATENT OFFICE.

JOHN P. BIHL AND HENRY J. BIHL, OF NEWPORT, KENTUCKY.

BATTERY LEAD CONNECTION OR CLAMP.

Application filed April 22, 1928. Serial No. 103,991.

This invention relates to detachable lead connections or clamps for the positive and negative terminal-posts of the opposite end-cells of storage-batteries that contain a multiple of jars or cells and are used, more particularly, in automobile and other like service.

Heretofore, the lead clamp-connections have been made to fit somewhat closely or rather too snugly on the said posts so that a free circulation of air around the joint, or the posts, has been prevented and whatever slight space there is in such joint has been the seat of an undue collection of acid-solution from the cells to cause corrosion, and a tough, hard deposit results that renders the removal of the said clamp-connections extremely tedious and difficult, and, otherwise, a very poor and defective connection and conductivity are present between the battery and the conductor-lines, such forcing tools or implements as wrenches, chisels, hammers, screw-drivers and the like being resorted to and required, to a greater or lesser extent, to both apply and to loosen or remove, the said clamp-connections, and constant danger of the said tools slipping from place and striking the cell filler-caps and otherwise breaking or injuring them being always possible and causing considerable expense and inconvenience in the handling and use of such battery-connections that thus become very objectionable and more or less costly and useless for any extended service.

Our invention aims to correct all the said defects, as there will be no hammer, chisel, wrench, screw-driver, or any such tools needed to apply our lead-connection, or to detach it, because it contains a pair of separable jaw-members that have serrated or grooved inner faces which readily impinge in clamping-place on the terminal-posts and are thus duly freed from any tendency of said acid-solution to seep into the joint, and thus, also, resulting in a clean connection at all times that can be made at a moment's notice and without skilled help being required in doing so.

The details of structure will be fully hereinafter described and elucidated in connection with the accompanying sheet of drawings, in which—

Figure 1 is a plan view of a storage-battery in present common use and showing one of our improved clamp-connections at the upper left-hand corner thereof, in the view,

and, also, one of the ordinary, objectionable snug-fitting old clamp-connections at the lower right-hand corner thereof, in the view, the latter old form being entered in this view for the sole and express purpose of showing the contrast between the said old form and our new form and for the convenience of more readily impressing the difference between them in the one battery in a more comprehensive manner than if several batteries were shown to bring out such contrast; Fig. 2, a disassembled perspective view showing all of the several parts of our improved clamp-connection; Fig. 3, a longitudinal section of the new clamp, including a broken-off end of the upper cable or conductor-wire that is inserted and soldered, in the usual manner, in using-place in the socket provided therefor in the main one of the two jaw-members of the clamp; Fig. 4, a transverse section of the new clamp taken on the dotted-line 4, 4, of Fig. 3 and including the cable-insert; and Fig. 5, a transverse section of the said new clamp taken on the dotted-line 5, 5, of Fig. 3, and showing the slip-bolt fastening at a right-angle to that of Fig. 3, for both clearness and accuracy of view.

A indicates the battery-casing having the usual separators or partitions B, B, for the independent placing or insertion of the cells C, D and E therein, the customary inter-cell connectors or conductors F being used for coupling the positive and negative terminal-posts of the several cells in due succession along the casing. The jars or cells are supplied with the usual caps G.

Our improved or new form of clamp-connection is shown in using-position on the round, positive terminal-post 6 in the far end of the left-hand cell C and the old form of clamp-connection (that it is our endeavor herein to rectify) is shown in contrasting place on the negative terminal-post 7 in the near end of the right-hand cell E of the battery seen in the main view, Fig. 1.

The said old form of clamp-connection has been composed of a cable-end socket member or part 8 that has a pair of corresponding semicircular jaws 9 and 10 extending integrally and laterally therefrom and thence is provided with integral, duly spaced and extended arms 11, 11, that are perforated in due alignment to receive a bolt 12 and nut 13 for drawing and securing the said semicircular jaws in tight and snug

clamping-place on the upper protruding end of the said negative terminal-post 7. Now, this old form fits entirely too snug upon the post and it causes the acid-solution to "suck-up" or seep very easily into the joint around the said post, where it becomes clogged and corroded, and firmly encrusted, very difficult to remove and then only with tools of some kind to do so, as first-mentioned.

10 Such a joint makes a very poor and defective connection on account of said corrosion and, when applying or putting on one of these old forms, a wrench must always be used to properly tighten it for the said snug closure of the said jaws 9 and 10 on the post 7, and it also requires a wrench to loosen it, and thus quite frequently additional tools, such as chisels and hammers, to pry or force it off of the terminal-post, when

15 excessive corrosion has taken place, the application of such force and the handling of such tools many times risking the slip of the wrench or one of the other tools to come into accidental breaking-contact with the too closely related cap or cover G of the cell E, wherein this old form is shown on the drawing, and in which the bolted jaw-ends of the clamp are directed toward the said cap G in dangerous proximity thereto. In

20 our new form of clamp, as seen in the upper left-hand end of Fig. 1, the main jaw-member 14 has a longitudinal integral tail-extension 15 that is narrowed down from a curved corner or face 16, and a socket 17 is

25 provided at its other end for the fastening-reception of the cable or terminal 18 leading from the positive-post 6 of the battery through our new form of clamp-connection. The said main jaw-member 14 of our said

30 new form of clamp has a tapered right-angled lateral-extension 19 whose inner curvular-face is serrated or sharp-toothed at 20, and it, also, has a transverse T-shaped outer end 21, as best shown in Fig. 2. The

35 tail-extension 15 of the jaw-member 14 is open-slotted or bifurcated, as also best seen at 22 in Fig. 2, for the purpose we will shortly refer to. The said T-shape outer end 21 of the tapered lateral-extension 19 of the main

40 jaw-member 14 is slightly rounded or beveled at 23 along its inner edge, as best seen in Figs. 2 and 3. A companion locker jaw-member 24 is provided for coaction with the main jaw-member 14, and it has a corresponding curvular inner face that is serrated or sharp-toothed at 25, an open-slotted flat arm or extension 26 being constructed at one end thereof and another open-slotted flat arm or extension 27 being constructed at

45 its other end, the last-named extension 27 coinciding with the open-slotted tail-extension 15 of the main jaw-member 14, and having laterally-turned or right-angled lugs or heels 28, 28, as best shown in Fig. 2, but,

50 also, well shown in Figs. 1, 3 and 5. A

horizontal bolt 29 is used to hold the two coinciding open-slotted ends 15, 22 of the jaw-member 14 and that 27 of the companion jaw-member 24 together when the two jaw-members are in assembled relation 70 in gripping-contact with the upper extended end of the terminal-post 6. The said bolt 29 has a square head 30 which seats against turning in the space provided between the laterally-turned heels 28 and the 75 corner or angle 31 at the beginning of the outwardly-swelled portion of the said companion locker jaw-member 24, and a wing-nut 32 is further provided at the opposite threaded-end of the bolt for impingement 80 against the flat face of the said open-slotted tail-extension 15, 22, of the main jaw-member 14 in the clamping-action of the new device claimed herein.

When assembling the said two jaw-members 14 and 24, the T-shaped outer end 21 of the lateral-extension 19 of the main jaw-member 14 is freely engaged with the open-slotted extension 26 of the companion jaw-member 24 so that said slotted extension 26 85 lies in free contact with the inner faces of the lateral wings of the said T-shape end 21, and, when the said wing-nut 32 is loosed, even very slightly, the said companion jaw-member 24 can be drawn lengthwise very 90 easily from engagement with the T-end 21 of the main jaw-member for the quick and easy, simple release of the jaw-member 24 and the bolt, together with its wing-nut, simultaneously, from any further locking or 95 clamping engagement with the said main jaw-member and thus releasing both jaw-members from engagement with the said terminal-post 6 without the use of any implements or tools at all, the wing-nut being 100 easily manipulated by the thumb and fingers, or, if a very tight engagement of the clamp is required or desired, a pair of ordinary pliers can be resorted to that will not 105 be in danger of breaking the adjacent top or cover of the cell, as the wing-nut part of the clamp is located near the outer side of the casing and well remote from said cover, while, it will be seen in Fig. 1, in connection 110 with the old form of clamp, how the ordinary fastening-nut 13 lies so close to the cell cover or lid G that there is always more or less danger of an implement breaking that lid in an effort to place or to remove 115 the nut, as hereinbefore stated.

120 It is obvious that the internal teeth or serrations of the pair of jaw-members 14 and 24 will hold in position on the post much better than the smooth form of inner faces of the jaw-members of the old form of clamp seen in Fig. 1, and that no undue corrosion in such a joint will likely ensue against the ready removal at any time of our new serrated form of air-vented clamp. In cold 125 weather, when it is more difficult, as a rule,

to remove battery terminal-post clamps, our form of clamp can be worked so easily and without any tools, by simply loosening the wing-nut and its two parts or jaw-members 5 then slipped apart or separated without effort, and, of course, just as easily put together or assembled in place.

There will be no greater cost to supply our new clamp over that of the old form, and 10 time, as well as other expense, can be materially saved thereby.

We claim:—

1. A battery lead connection or clamp comprising, in combination, a pair of independent separable jaw-members each of the latter having internally serrated or toothed arc-shape main-portions, one of said jaw-members being the main one that is provided at one end with a laterally-projecting T- 20 shape arm and a socket for the securing-end of the lead wire or cable and at its other end provided with an open slot or recess, and the other one of said jaw-members being a locking one that is provided with an open 25 slot or recess at one end for co-engagement with the said T-shape arm of the main jaw-member and at its other end provided with an open slot or recess that coincides and registers, in use, with the open slot or recess 30 of the said main jaw-member, and a square-headed bolt that is adapted to engage the said registering open-slotted ends of the main and locking jaw-members and provided with a winged fastening-nut, substantially as shown and described.

2. In a battery lead-connection, the combination of a main internally-toothed arched

jaw-member having a T-shape lateral arm and a cable-socket at one end and a pair of narrowed and spaced arms or projections or otherwise open-slotted at its other end, a companion arched, internally-toothed locker jaw-member provided independent of the said main jaw-member and having an open-slotted formation at one end to interlock 40 and coact, in use, with the said T-shape lateral arm of the main jaw-member and, also, having at its opposite end a pair of narrowed and spaced arms or projections or otherwise open-slotted to coincide and coact 45 with the said open-slotted end of the main jaw-member, outwardly-turned heels or lugs at the outer ends of the said spaced arms of the locker jaw-member to form a detent-seat, a bolt having a square head at one end 50 adapted to seat, against turning, in said detent-seat of the locker jaw-member, and a winged fastening-nut adapted to engage the threaded outer end of the said bolt with its base in contact with the outer face of the 55 said narrowed spaced arms at one end of the main jaw-member, the whole being arranged and coupled together in such a free and easy manner as to form a ready cast-off when it is desired to disconnect the clamp from connecting-place at the upper end of the battery terminal-post, and the said two internally serrated or toothed jaw-members having free air-vent passages between them and the post, substantially as shown and described. 60 65 70

In testimony whereof we have hereunto affixed our signatures.

JOHN P. BIHL.
